UNITED STATES PATENT OFFICE.

BENJAMIN G. VAN DYKE, JR., OF JACKSON, OHIO.

AUTOMATIC TRAIN STOP OR SIGNAL.

Application filed February 19, 1925. Serial No. 10,211.

To all whom it may concern:

Be it known that I, BENJAMIN G. VAN DYKE, Jr., a citizen of the United States, residing at Jackson, in the county of Jackson and State of Ohio, have invented new and useful Improvements in an Automatic Train Stop or Signal, of which the following is a specification.

My invention relates to new and useful improvements in an automatic train stop or signal, and particularly embodies an electrically actuated mechanism controlled by the ordinary track circuit to actuate the valve of an air brake system, a signal, either visible or audible, or other similar devices to stop a train or produce signals to indicate the condition of the road ahead.

One of the principal objects of the invention is to provide a plurality of electrical circuits the operations of the majority of said circuits being dependent upon the operation of a primary circuit controlled by a track circuit of a railway track, said primary circuit when interrupted by a train occupying a block, broken rail, open switch, or the like causing the track circuit to be put in operative condition to break the train circuit and thereby complete the operating circuit of the brake valve, signal or the like.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:—

Fig. 1 is a fragmentary sectional side elevation of a track, a vehicle thereon carrying component parts of my device for cooperation with the parts at the side of the track and showing the electrical circuits and the operating or operated elements diagrammatically.

Fig. 2, is a diagrammatic view of the track circuits in a number of adjacent blocks illustrating the arrangements for producing "caution" and "stop" signals.

Fig. 3, is a diagrammatic view of the two vehicle and operating circuits which are used in conjunction so that one will give

stop signals and the other will give caution signals.

In carrying out my invention as here embodied, 2 represents a railroad track having an electromagnet or electromagnets 3 located adjacent thereto in some desirable position for cooperation with the armature 4 having one end connected to a bracket 5 or its equivalent while the other end is free to move in a vertical direction but normally drawn upward by the spring 6 against the bracket 7 or its equivalent which latter acts as a stop to limit the upward movement of said armature. The brackets 5 and 7 are insulated from each other in any suitable manner, the insulating medium as here shown comprising a suitable housing 8 carried by the support 9 which is fastened by hangers 10, or their equivalents, to a railway vehicle 11 such as a locomotive, a tender or a car.

In order to protect the armature 4 and its component parts against damage a suitable guard 12 may be placed at both ends of the housing 8 and similar guards 13 may be placed at both ends of the electromagnet or electromagnets 3 for the same purpose.

The reference numeral 14 denotes a movable element of a signal, air brake valve or similar device and with this movable element is associated an electromagnet 15 to be energized from a source of electrical energy 16 such as a battery and in addition to the electromagnet 15 and the source of electrical energy 16, the operating circuit comprises suitable conductors 17 and 18, an armature 19 with which the conductor 18 is connected, a contact 20 and a conductor 21 connecting the contact with the electromagnet 15. This circuit is closed when the armature 19 engages contact 20 so that the electromagnet 15 will be energized and actuate the moving element 14 which, if a part of an air valve, will apply the air brakes or, if a part of a signal device, will actuate such signal to audibly or visibly indicate the condition of the road ahead. The operating circuit just mentioned is completed upon the breaking of the vehicle circuit which in addition to the armature 4 and source of electrical energy 16 includes conductors 22 and 23, the electromagnet 24 and the conductor 25.

The vehicle circuit is broken by the operation of the armature 4 which is drawn away from the contact bracket 7 when the

track magnets 3 are in a track circuit which includes conductors 26 and 27, an armature 28 to which the conductor 26 is connected, a contact 29, a conductor 30 and a source 5 of electrical energy 31 such as a battery. The magnet circuit is normally maintained open by a signal circuit which includes an electromagnet 32 associated with the armature 28 for normally holding said armature 10 out of engagement with the contact 29, a conductor 33 leading from the electromagnet 32 to track circuit wire 34, which may include a part of a track rail, a conductor 35 leading from the electromagnet 32 to track circuit wire 36 for completing the circuit.

It is to be understood that there are two sets of track magnets, "caution" and "stop", a set adjacent each track rail, preferably on 20 the outside thereof and also two sets of armatures one on each side of the railway vehicle as illustrated in Figs. 2 and 3 wherein 103 represents the track magnets for producing the "caution" signals and one of 25 these "caution" track magnets is along side the track of each block said blocks being represented by the reference letters A, B and C.

The electromagnets 103 of the second trackside circuit are for cooperation with 30 the armature 104 of the vehicle circuit shown at the left-hand side of Fig. 3 which is the same as the other vehicle circuit above described and illustrated at the right-hand side of Fig. 3 in addition to the showing 35 in Fig. 1. The armature 104 is pivoted at 105 and normally moved in one direction by a spring 106 to engage a contact 107.

A movable element 114 of a signal or the like within the vehicle, preferably adjacent 40 the movable element 14, is associated with an electromagnet 115 to be energized from a source of electrical energy 116 and in addition to the magnet 115 and electrical source 116, the operating circuit includes 45 conductors 117 and 118, an armature 119, a contact 120 and a conductor 121 leading from said contact 120 to the magnet 115. The operating circuit referred to is completed upon the breaking of the vehicle 50 circuit which in addition to the armature 104 and source of electrical energy 116 includes conductors 122 and 123, the electromagnet 124 and conductor 125.

The vehicle circuit is broken by the 55 operation of the armature 104 which is drawn away from the contact 107 when a track magnet 103 in a second trackside circuit is energized, which second trackside circuit includes a conductor made up of a wire 126, 60 a portion of a track rail and a wire 226 connecting one side of the "caution" magnet 103 with one side of a battery 31 in the first trackside circuit through the conductor 26, armature 28, contact 29 and conductor 30, while the other side of the "cau-

tion" magnet 103 is connected by a conductor 127 with the other side of the battery 31, as through a portion of conductor 27.

From the foregoing description it will be obvious that when a vehicle, conventionally represented at 100 is in block C the track battery 101 in said block will be short circuited thereby causing the armature 28 in the first trackside circuit to drop and engage the contact 29 so as to close both 75 the primary and second trackside circuits through the battery 31 thus energizing the "stop" magnet 3 in block B and the "caution" magnet 103 in block A while all of the other track magnets will be unaffected. 80 A train proceeding through block A will have its armature 104 acted upon by the magnet 103 so as to open the vehicle circuit and close the signal circuit whereby the magnet 115 will be energized and operate the movable element 114 of the signal 85 thereby giving the "caution" signal to the operator of the train.

As the train proceeds into block B the armature 4 will be actuated by the magnet 3 to open the vehicle circuit and close the "stop" signal circuit which includes magnet 15 so as to actuate the movable element 14 which may be a part of a "stop" signal or the brake system so that the operator 95 will be given the "stop" signal or the brakes applied or both.

Although I have shown the most simple way to accomplish the desired object I do not wish to be limited in any way thereto as many changes and modifications might be made without departing from the scope of the invention and all such changes are contemplated by me and are considered 100 within the purview of the appended claims.

Having thus fully described my invention, what I claim as new and useful is:—

1. An automatic train stop or signal comprising an electrical circuit controlled by the operation of a track circuit, another electrical circuit including an electromagnet, means in said electrical circuits whereby the opening of the first circuit will close the second circuit, a railway vehicle, an electrical circuit in said vehicle, said last mentioned circuit including means actuated by the electromagnet in the second named circuit to open said vehicle circuit, an operating circuit including parts of the vehicle circuit, means in the last two circuits whereby the operating circuit will be closed upon the opening of the vehicle circuit, a movable member and means in the operating circuit to actuate said movable member when said operating circuit is closed.

2. The combination with a railway track and a railway vehicle of an electromagnet located adjacent the track, guards protecting said electromagnet, an electric circuit including said magnet, a source of electrical 130

energy and the armature of a relay, another electric circuit including the magnet of said relay, a source of electrical energy derived from a track circuit to energize the relay and open the first named circuit, the operation of the track circuit breaking the circuit through the relay and closing the circuit through the electromagnet to energize the latter, an armature on the railway vehicle, guards to protect said armature, a third electric circuit including said second armature, a battery and the magnet of another relay, means to normally hold said armature in a position for closing said third

circuit, a fourth electric circuit including the battery of the last named circuit, the armature of the last named relay, and a magnet whereby the energizing of the electromagnet will actuate the armature on the railway vehicle to open the third mentioned circuit thereby closing the fourth mentioned circuit and energizing the last mentioned magnet, and means controlled by said last named magnet to operate a signal.

In testimony whereof, I have hereunto affixed my signature.

BENJAMIN G. VAN DYKE, JR.
